UNITED STATES PATENT OFFICE.

EDWIN RINGOLD, OF BOSTON, MASSACHUSETTS, ASSIGNOR TO NATIONAL CASH REGISTER COMPANY, OF JERSEY CITY, NEW JERSEY, A CORPORATION OF NEW JERSEY.

DESIGN FOR A CASH-REGISTER CABINET OR CASING.

SPECIFICATION forming part of Design No. 36,768, dated February 2, 1904.

Application filed November 14, 1903. Serial No. 181,247. Term of patent 7 years.

To all whom it may concern:

Be it known that I, EDWIN RINGOLD, a citizen of the United States, residing at Boston, in the county of Suffolk and State of Massachusetts, have invented a new, original, and ornamental Design for Cash-Register Cabinets or Casings.

In the accompanying drawings, forming part of this specification, Figure 1 shows a three-quarters front perspective view, and Fig. 2 shows a three-quarters rear perspective view, of a cash-register cabinet or casing having the design of my present invention.

What I claim is—

The ornamental design for a cash-register cabinet or casing as shown.

In testimony whereof I affix my signature in the presence of two witnesses.

EDWIN RINGOLD.
